CLAIM

The ornamental design for a reader for medical or nonmedical diagnostic use with integrated test strip, as shown and described.

DESCRIPTION

FIG. 1 is a top, front and left side perspective view of the reader for medical or nonmedical diagnostic use with integrated test strip of our design.

FIG. 2 is a bottom, front and right side perspective thereof. FIG. 3 is a left side view thereof, the right side being a mirror image thereof.

FIG. 4 a front elevation view thereof.

FIG. 5 is a rear view thereof.

FIG. 6 is a top plan view thereof; and,

FIG. 7 is a bottom plan view thereof.

Elements drawn in broken lines show environmental aspects of the reader for medical or nonmedical diagnostic use with integrated test strip which form no part of the claimed design.
